(57) **CLAIM**

The ornamental design for a golf cart light, as shown and described.

DESCRIPTION

FIG. 1 is a rear, bottom perspective view of a golf cart light design showing new design.

FIG. 2 is a front, top perspective view of the golf cart light.

FIG. 3 is a front view of the golf cart light.

FIG. 4 is a rear view of the golf cart light.

FIG. 5 is a left view of the golf cart light.

FIG. 6 is a right view of the golf cart light.

FIG. 7 is a top view of the golf cart light.

FIG. 8 is a bottom view of the golf cart light.

FIG. 9 is a perspective view of the golf cart light installed on a golf cart shown in broken lines; and,

FIG. 10 is an enlarged view of the portion encircled in FIG. 9.

The broken lines shown in the drawings represent environment that form no part of the claimed design. The broken line circle in FIGS. 9-10 is included for the purpose of indicating the enlarged area.
